UNITED STATES PATENT OFFICE.

MURVIN E. ARKILLS, OF CHICAGO, ILLINOIS.

PNEUMATIC-HAMMER SAFETY DEVICE.

1,267,163.

Specification of Letters Patent. Patented May 21, 1918.

Application filed December 21, 1916. Serial No. 138,161.

To all whom it may concern:

Be it known that I, MURVIN E. ARKILLS, a citizen of the United States, residing at Chicago, in the county of Cook and State 5 of Illinois, have invented certain new and useful Improvements in Pneumatic-Hammer Safety Devices, of which the following is a specification.

The invention has for its primary object 10 provision of efficient mechanism for holding the tool to its seat, said mechanism capable of being quickly released and engaged relative to the tool without the possibility of loss of parts or of personal injury, and being automatic in its releasing and clamping 15 action when actuated by the operator and proof against accidental operation.

In order that the invention may be readily understood by those skilled in the art preferred and modified embodiments of the 20 same are set forth in the accompanying drawings and in the following detailed description based thereon. Obviously the invention is susceptible of embodiment in other 25 and varied constructional forms, wherefore it will be understood that the drawing and description are to be taken in an illustrative and not in an unnecessarily limiting sense.

In the drawings—

30 Figure 1 is a composite view showing a pneumatic hammer embodying the invention, partly in side elevation and partly in longitudinal section;

35 Fig. 2 is a transverse section on the line 2—2 of Fig. 1;

Fig. 3 is a similar section on the line 3—3 of Fig. 1;

Fig. 4 is a detail view of one of the clamping jaws;

40 Figs. 5, 6, 8 and 9 are fragmentary longitudinal sectional views of modifications;

Fig. 5^a is a detail view of one of the clamping jaws shown in Fig. 5; and

45 Fig. 7 is a transverse section on the line 7—7 of Fig. 6.

The invention is herein shown and described in connection with a pneumatic hammer of the general type of that shown in the patent to Lelois 1,138,877, but constitutes 50 an improvement thereover in the manner of mounting and operation of the tool holding jaws, whereby the releasing and clamping action of the jaws is rendered automatic and disassociation of the parts is effectually precluded.

Having particular reference to Figs. 1 to

4 of the drawings, reference numeral 11 designates the cylindrical shell or barrel of a pneumatic hammer of ordinary construction within which is adapted to operate the 60 piston-hammer, not shown. Inserted in the forward end of the barrel is a die or tool 12 by means of its shank 13. Immediately to the rear of the tool head 12 is a portion of reduced diameter 14 and immediately to 65 the rear thereof is a shoulder 15, the forward and rear faces of the shoulder 15 forming abutments to limit the reciprocation of the tool under the impact of the hammer.

A short distance to the rear of the forward end of the barrel 11 is formed an annular groove 16 and forwardly of said groove the diameter of the barrel is slightly reduced. A series of segmental lever jaws 70 75 17 are arranged about the reduced end 11^a of the barrel with toe flanges 18 resting in the groove 16. Each of these jaws has an outwardly extending heel flange 19 and an inwardly extending lip flange 20 at its forward end. Taken together, the plurality of jaws 17, individually segmental in shape, constitute a complete circle enveloping the tool in its reduced portion 14, the lip flanges 20 extending closely adjacent the reduced 80 85 portion 14 of the tool and within the space included between the head 12 and the shoulder 15 of said tool. It will be readily understood that when held together to form a complete circle the lip flanges 20 will 90 serve as a forward abutment for the shoulder 15 to limit the forward movement of the tool 12. In Fig. 1 the jaws are shown in clamping 95 relation to the tool.

Encircling the forward portion on the 95 barrel of the hammer is a sleeve 21 having a knurled actuating portion 22 and a removable forward extension 23 detachably connected to the sleeve 21 by means of the threads 24. The sleeve 21 is undercut at 100 25 as is also the barrel at 26 provided with an exterior groove to accommodate the leaf spring 27 when the latter is depressed. On the forward end of the sleeve 21 is provided a shoulder 28 and the forward end of 105 the extension 23 is inwardly flanged to provide a shoulder 29, which closely envelops the forward ends of the jaws 17.

Assuming the several parts of the device to be in the position shown in Fig. 1, if it 110 be desired to release and remove the tool 12 from the device the leaf spring 27 is de-

pressed into the groove 26 and by means of the knurled portion 22 of the sleeve 21 the latter is moved to the rear carrying with it the sleeve extension 23 and causing the flange 29 to move back out of enveloping relation to the forward ends of the jaws and to engage the heel flange 19 of the jaws. It will be seen from Fig. 1 that that portion of the rear 10 end of the jaw is beveled, and the striking of the flange 29 against the heel flange 19 will cause the jaw to rock upon the toe flange 18, the forward ends of each of the jaws moving outwardly radially so that the 15 several jaw segments instead of constituting a closed cylinder will form a flaring or trumpet-shaped mouth to the hammer, the several jaws being separated. The tool 12 may now be readily removed from within 20 the jaws and the forward end of the barrel. The same tool having been replaced or another substituted, the sleeve 21 and its extension 23 is moved forward, the flanges 29 of the sleeve extension riding upon the several 25 segmental jaws and causing the same to rock inwardly to a clamping position about the tool as before, the flange 29 and the shoulder 28 coöperating to hold the jaws in the position indicated in Fig. 1, while the spring 27 30 will snap to the position shown against the knurled portion of the sleeve 21 and thus prevent its accidental retraction to release the jaws.

In this embodiment of the invention I have 35 shown the jaws as seven in number. Obviously there may be more or less. There should be three or more in order to facilitate the rocking of the same upon their fulcras in the groove 16.

40 In Fig. 5 is shown a form of construction in which a one piece sleeve 80 is used the forward movement of which is limited by impingement against a flange 81 formed upon each jaw 82 while its movement to the 45 rear in the locked position is restricted as before by the spring 83 and its rearward movement in the unlocked position is limited by means of the screw head 84. In this form of the invention the segmental jaws 82 are 50 provided with toe flanges 85 fulcrumed within the annular groove 86. Instead of providing positive means such as the heel flanges 19 for rocking the jaws to release the tool as in the construction formerly described, each of the jaws 82 has formed 55 therein by stamping an integral spring tongue 87 which bears downwardly upon the forward end of the barrel and tends to force the jaws upwardly causing the several 60 jaws to separate radially as before to permit the withdrawal of the tool 12. The range of movement of the sleeve to the rear is such as not to entirely clear the jaw and consequently the several jaws are prevented from 65 disassociation.

In Fig. 6 is shown another form of construction, the segmental jaws 40 having the forward inturned lip flange 41, the toe flange 42 and the heel flange 43, the jaws adapted to rock within the groove 44. A sleeve 45 is 70 provided having a helical slot 46 within which plays a pin 47 seated in the barrel of the hammer. In this case a sleeve extension 48 is screw threaded upon the forward portion of the sleeve 45 and has an inturned 75 flange 49 between which and the forward end of the sleeve proper 45 the heel flanges 43 of the jaws are confined. To the barrel at the rear of the sleeve 45 is secured by means of a screw 50 a spring 51 which extends into 80 an undercut face 52 in the rear of the sleeve. The upper wall or roof of the undercut portion 52 is corrugated or roughened as indicated at 53 to frictionally engage with the forward end of the spring 51. It will be 85 readily understood that when the sleeve 45 is rotated, the engagement of the pin 47 in the slot 46 will cause the sleeve 45 to move to the rear thus rocking the jaws 40 upon the toe flange 42. The frictional engagement 90 between the forward end of the spring 51 and the roughened surface 53 will cause the angular adjustment of the sleeve 45 to be maintained either in the locked or unlocked 95 position of the jaws 40.

In Fig. 8 is shown a form of construction in which the jaws 60 are themselves of spring metal having the forward lip flange 61, the toe flange 62 seated in an annular groove and with an extension 63 bearing upon the beveled forward end of the barrel. The one piece sleeve 64 is arranged to reciprocate so as to close the spring jaws 60 or to permit them to open under the influence of the spring extension 63 bearing upon the hammer. The movement of the sleeve 64 to the rear is limited in the clamped position of the tool by the spring 65 and in its rearmost position with the clamping jaws expanded by impinging against the head of the screw 110 66, while its forward movement is limited by its shoulder 67.

In Fig. 9 is shown yet another form of construction wherein the spring jaws 70 having the forward lip flange 71 are at the rear 115 bent upon themselves to form the toe flange 72 and the spring extension 73. The jaw segments are confined or permitted to expand by the one piece sleeve 74 arranged to reciprocate upon the barrel of the hammer 120 and provided with a longitudinal slot 75 within which plays a pin 76 mounted in the barrel. The rearward movement of the sleeve 74 is limited in the closed position of the jaws by the spring 77.

125 It will be observed that in all of the embodiments of the invention herein set out by way of illustration, the tool holding jaws are arranged to open automatically as the sleeve is actuated, either by the rocking of 130

the jaw segments as an entirety, they being rigid as in Fig. 1, or by reason of their inherent elasticity when the confining action of the sleeve is removed. In their expanded 5 position, they are yet confined by the sleeve within the groove of the barrel in such manner that they cannot become loose and disassociated from the other parts of the device except by affirmative action of the operator 10 where it is desired to replace or to obtain access thereto for some other reason. In the latter event, the sleeve extension 23 or 48 would be unscrewed in that form of the device shown in Figs. 1 and 6, or the screw 34 15 or 66 or 76 would be removed in the device shown in Figs. 5, 8 and 9 so as to permit the sleeve to move to the rear a sufficient distance to clear the jaws.

I claim:

20 1. Tool holding mechanism for pneumatic hammers comprising a plurality of jaws carried by the hammer barrel and embracing a tool, means to tilt the jaws to expand their forward ends whereby to release the tool and to contract the jaws whereby to clamp the tool.

25 2. Tool holding mechanism for pneumatic hammers comprising three or more segmental jaws carried by the hammer barrel and embracing a tool, and means to tilt the jaws to expand their forward ends whereby to release the tool and to contract the jaws whereby to clamp the tool.

30 3. Tool holding mechanism for pneumatic hammers comprising a plurality of segmental jaws fulcrumed at their rear ends on the hammer barrel and having tool engaging flanges at their forward ends, and a sleeve 35 movable on the barrel and acting on the

jaws to rock the same into and out of clamping relation to the tool. 40

4. Tool holding mechanism for pneumatic hammers comprising a plurality of segmental jaws, the jaws fulcrumed at their rear ends to tilt from a general parallel position 45 clamping a tool to an expanded flaring position releasing the tool, and a sleeve embracing the jaws and movable on the hammer barrel.

5. Tool holding mechanism for pneumatic hammers comprising a plurality of segmental jaws having rear and forward flanges engaging the hammer, barrel and tool, the jaws fulcrumed on their rear flanges to tilt from a general parallel position 55 clamping the tool to an expanded flaring position releasing the tool, and a sleeve embracing the jaws and movable on the hammer barrel.

6. Tool holding mechanism for pneumatic 60 hammers comprising a plurality of segmental jaws having inwardly extending forward tool engaging flanges and inwardly and outwardly extending rear flanges, the barrel grooved to receive the inwardly extending rear flanges, a sleeve movable longitudinally of the barrel and embracing the jaws, and means carried by the sleeve to engage the outwardly extending rear flange of the jaws upon the movement of the sleeve to 65 the rear to tilt the jaws on their inwardly extending rear flanges to an expanded flaring position whereby to release the tool. 70
